UNITED STATES PATENT OFFICE.

CLYDE K. TURLEY, OF IRONTON, OHIO.

FOLDING EXTENSION FOR CAR-STEPS.

SPECIFICATION forming part of Letters Patent No. 760,663, dated May 24, 1904.

Application filed February 15, 1904. Serial No. 193,484. (No model.)

To all whom it may concern:

Be it known that I, CLYDE K. TURLEY, a citizen of the United States, residing at Ironton, in the county of Lawrence and State of Ohio; have invented a certain new and useful Improvement in Folding Extensions for Car-Steps; of which the following is a specification.

My invention relates to the improvement of car-steps, and has particular relation to the improvement of folding or adjustable car-steps.

The objects of my invention are to provide, in conjunction with the usual fixed steps of a car, one or more folding step-sections, to provide improved means for hinging said step-sections one with the other and with the last fixed step of the car, to provide improved means for operating and controlling said folding step-sections, and to produce other improvements the details of construction of which will be more fully pointed out hereinafter. These objects I accomplish in the manner illustrated in the accompanying drawings, in which—

Figure 1 is a transverse section on line $\alpha\alpha$ of Fig. 3 through a portion of the platform and steps of a car, showing my additional folding steps in connection therewith and in position for use. Fig. 2 is a similar sectional view showing the position of the parts when the lower step elements are folded against the under side of the lower fixed step. Fig. 3 is a partial front elevation of the car-steps and platform, showing for the sake of clearness the outer side of the car broken away; and Fig. 4 is a detail view in perspective, showing the rear or under sides of portions of the folding step-sections, together with the stop-hinge which connects the same.

Similar numerals refer to similar parts throughout the several views.

1 represents a portion of the end of a car-body through the platform, and 3, 4, and 5 the usual fixed steps, which are mounted between the step sides 6 in the well-known manner.

45 My folding step attachment preferably consists, as shown, of two sections 7 and 8, the upper section forming when the same are in position for use a back and support for the lower horizontal step-section. These sections

7 and 8 may be constructed either of wood or metal, preferably of the latter, and in case metal is employed the projecting tubular hinge members 9, which jointedly connect the step members 7 and 8 and which are adapted to receive the usual hinge-pin 10, are formed integral with said step members. In uniting the member 7 with the lower fixed wooden step 5 the hinge-plate 11 is secured to the under side of said step 5 and let into the latter until flush therewith, as shown more clearly in Fig. 4. The rear portions of the hinge members 9 and 11 are formed with projecting stop lips or shoulders 11^a and 9^a, the beveled faces of these shoulders contacting with each other when the step back member 7 and step 5 are at right angles with each other, as shown, this engagement of said shoulders 11^a and 9^a operating to limit the outward swinging movement of the member 7. In forming the integral hinge parts which unite the step members 7 and 8 the same stop-shoulder projections are produced. Pivoted within the casing of the end of the car and projecting therefrom is a shaft 12, with which is connected on the inner side of the outer wall of the car end an arm 13, the latter extending within the casing or between the inner and outer walls of the car end and having connected with its outer end a downward-extending and outwardly-inclined bar 14, which passes through an opening in the side of the car-body adjacent to one corner thereof and which has its lower end pivotally connected with a laterally-projecting pin 15 of the lower folding step member 8. This pin 15 may be formed integrally with said step member or secured thereto, as shown. With the outer end of the shaft 12, which projects on the outer side of the car end at a suitable point above the platform, is connected the lower end of an upwardly-extending operating-lever 16, the latter preferably working in a suitable form of keeper 17, which is secured to the car end, and which keeper may be provided at opposite ends with pin-holes 18 to receive a stop-pin 19, which also is adapted to engage an opening in the lever 16, and thus permit of said lever being locked either in its rear or

forward position. It is obvious, however, that other well-known means may be employed for locking said lever in the desired position.

It will be understood that when the lever 5 is thrown to the position indicated in Fig. 1 of the drawings the bar 14 will have been forced to its downward limit, with the result that the lower step member 8 will be supported in a horizontal position for use as a 10 step, and that by this means the usual car-steps are provided with an extension which is brought sufficiently near the ground or station-platform to permit of its convenient use by passengers and obviate the necessity of 15 employing portable footstools or other means for reaching the steps. When the lever 16 is thrown to the opposite end of its keeper 17 in the manner indicated in Fig. 2 of the drawings, it is obvious that the upward movement 20 of the bar 14 will be sufficient to close the back member 7 against the under side of the step 5 and the step member 8 against the member 7, and when said step members are 25 in such folded position it is evident that the same will in no way interfere with platforms or other obstructions at the side of the track.

From the construction which I have shown and described it will be seen that a simple and reliable step extension is provided for cars which may be readily and easily operated. 30

Having now fully described my invention, what I claim, and desire to secure by Letters Patent, is—

In a folding extension for car-steps, the combination with a car-body and a plurality of 35 fixed steps depending therefrom, of a riser and a tread hinged together, a shoulder 9^a having an angular face formed on the riser, a hinge member set into the lowermost of the fixed steps so as to lie flush therewith and 40 having a swinging engagement with the riser, an angular shoulder formed on the said member and adapted to contact with the shoulder 9^a to hold the riser and tread in substantially right-angular relation when they are extended, 45 a bar pivotally connected to the tread, and a lever pivotally connected to the bar for raising and lowering the riser and the tread.

CLYDE K. TURLEY.

In presence of—

FRED W. NEWMAN,
WILLIAM J. DORAN.
